CHECK HANDLING APPARATUS

Charles J. Breitenstein and Donald E. Hooker,
Chicago, Ill., assignors to Raymond T. Moloney,
Chicago, Ill.

Application March 14, 1936, Serial No. 68,852

16 Claims. (Cl. 312—67)

The invention primarily relates to a check handling apparatus, although as will appear, the apparatus is obviously useful also in handling coins and tokens.

5 In apparatus of this kind for dispensing the checks, or the like, from an upright magazine there is usually provided an ejector, which may be in the form of a slide, operable across the lower end of the magazine to eject the checks therefrom. The ejector may be driven by an electromagnetic motor device, such as a motor, electromagnet or solenoid, and every time the device is energized the ejector is operable to make a stroke relative to the magazine. The ejector is 10 formed with an opening registerable with the lower end of the magazine so that a check may gravitate into the opening and be carried over a tight bottom by the ejector to a point of discharge, whence the check drops through the ejector opening to be dispensed in a manner common in this art. The thickness of the ejector slide in relation to the thickness of the checks determines the number of checks to be handled on each 15 stroke of the slide. Usually the slide is thick enough to receive one check; but sometimes as in the present disclosure, it is thick enough to receive and move two superimposed checks.

Sometimes it is desirable simultaneously to handle and dispense more checks or coins than it 20 is possible for one ejector or slide of a given thickness to receive and move in a single stroke, and accordingly this invention provides an improvement whereby a plurality of ejectors are arranged in a manner relative to the magazine to enable 25 one, or several, or all of them to operate, whereby any desired number of checks, within limits, may be handled and dispensed in a single stroke of the ejector mechanism.

The object of the invention is to provide an improved check handling mechanism.

Another object is to provide such a mechanism in which a plurality of independently and conjointly movable ejectors are provided for enabling any number of checks, within limits, to be handled 30 and dispensed, as desired.

Still another object is to provide an improved, simplified control mechanism for determining whether one or more ejectors are to handle checks in a single stroke of the dispensing operation.

Another object is to provide a device operatively associated with the ejector mechanism to compensate automatically for varying thicknesses of checks handled to prevent jamming of the dispenser.

Other important objects of the invention will be apparent to those skilled in this art as the disclosure is more fully made.

In carrying out the invention in a practicable embodiment there may be provided a base carrying a motor device, such for example as an electric motor having a movable part connected to drive an ejector structure over a tight bottom and across the lower end of an upright magazine containing the checks, coins or tokens to be handled 5 and dispensed. The checks are loaded into the magazine, one on top of the other, in a stack or column with the checks gravitating to the bottom of magazine and resting on a solid part of an ejector. The ejector preferably, though not necessarily, comprises a plurality of independently movable flat slides arranged in a pack one above the other and movable by a carrier reciprocated by the motor. Each slide contains a check receiving opening operative when moved 10 under the magazine to receive two checks by gravity since each slide is of a depth equal to the thickness of two checks.

When the lower slide has thus received two checks, the slide in its movement moves its two checks over the tight bottom to a point of discharge. If the lower two slides are moved together then four checks will be handled. If the three lower slides move together then six checks will be handled, and so on. A simple control 15 means is included in the mechanism to predetermine how many of the slides are to operate conjointly with the lower or main slide. A thickness compensator is provided to prevent jamming 20 of the slides with the checks in the magazine when slightly worn checks are handled. So much 25 will suffice in presenting a general view of the structure shown in detail in the accompanying 30 sheets of drawings, wherein:

Figure 1 is a full size plan view of the improved 35 check handling apparatus shown as a unit carried on a base plate;

Figure 2 is a detail, sectional view taken along the line 2—2 of Figure 1, on an enlarged scale and looking in the direction of the arrows;

Figure 3 is a fragmentary, longitudinal cross 40 sectional view through the unit taken along the line 3—3 of Figure 1, looking in the direction of the arrows;

Figure 4 is a side elevational view of the unit;

Figure 5 is an end elevational view of the unit;

Figure 6 is a detail, enlarged, perspective view to illustrate the operative relationship between a control member and the pack of dispenser 45 ejectors, or slides; and,

Figure 7 is a similar view, showing these parts in a somewhat different relative position.

Preferably, though not necessarily, the apparatus is in the form of a unit mounted on a horizontal base plate 10, one end of which is formed with a hole 11 of a size to permit a check or the like to drop therethrough, said plate at its bottom side including a sleeve 12 surrounding the hole.

An inverted U-shaped block 13 is formed with 10 or carried on the base, the same including an upstanding socket portion 14 in which is removably mounted an upright cylindrical magazine 15 for carrying a stack, or column of checks or coins in a manner causing gravity to feed the checks, or the like, flatwise, downwardly into the block 13. One side of the block 13 carries spaced pins 16 for securing a bar 17 in place, said bar having one end bent downwardly as at 18 to form a stop as will later appear. The bar 17 is slotted as at 19 so that the end 18 may be moved in or out relative to the end of the block 13 for 20 adjustably setting the end 18. The magazine 15 as shown in Figure 3 is offset with respect to the check drop opening 11 in the base 10.

25 A main, or lower check slide 20 is slidably guided through the tunnel in the block 13 at one end, where the slide is formed with a check receiving opening 21 and since the slide is of a thickness equal to the thickness of two superimposed checks it follows that the opening 21 when in registration under the magazine 15 may receive two checks to be moved by the slide 20. The opposite end of the slide 20 has a slot 22 for guiding and limiting the extent of its to and fro movement by means of a headed pin 23 mounted on the base 10.

The main, or bottom slide 20 is formed with an integral, upright wall 24 having a vertical slot 25 included therein. Alongside the block 13 the base 10 carries any suitable motor device which in the present instance is in the form of an electric motor 26 having a movable part or shaft 27 carrying a worm 28, which meshes with and drives a worm wheel 29. The latter wheel 29 is turnable with a cross shaft 30 suitably journaled in brackets 31. The shaft 30 is projected toward the wall 24 and at that end carries and turns a disk or blank wheel 32 on which is mounted an eccentric pin or roller 33 movable in the slot 25. It can be seen that the eccentric pin wheel drives the slotted wall and thus serves to reciprocate the main slide 20 to and fro through the block 13 and under the magazine 15.

The end of the main slide 20 which is projected through the block 13 is abutted by a lever 34 pivoted by a pin 35 on the base plate 10, said lever being pulled by a spring 36 connected between the lever and plate 10 as shown. Obviously, when the slide 20 is moved to dispense checks it does so against the force of the spring 36 which spring therefore supplies a force through the lever 34 for positively returning the main slide to its starting position. An adjustable set screw stop 37 is carried on the plate 10 to limit the movement of the main slide 20 in relation to the magazine 15.

The main slide 20 along one edge carries a horizontal and laterally extending carrier plate 38 by means of a pair of screws 39 mounted in the slide 20. Slots 40 are provided whereby the carrier plate may be adjustably set within limits along the main slide 20.

The end of the plate 38 toward the magazine 15 is upturned to provide an upright wall 41 arranged at substantially a right angle to the

direction of travel of the main slide 20. This wall is formed with a slot 42 through which is passed a pin 43. The pin 43 carries a rack tooth bar 44, the said bar having slots 45 riding pins 46 carried on the wall 41, said pins having heads 47 to hold the bar 44 in place. Obviously, the rack bar 44 is rideable on the pins 46 transversely in parallelism with the wall 41. The end of the bar 44 adjacent the main slide 20 is formed with steps numbered 48, 49 and 50 for a purpose 10 later to appear. The upper edge of the bar 44 is formed with rack teeth as shown.

Above this bar 44 the wall 41 carries a pivot pin 51 on which is pivotally mounted intermediate of its ends, a double pawl lever 52 having 15 stop teeth at opposite ends to engage the teeth on the rack bar 44. At one end the upper edge of the pawl lever 52 is formed with a right angular extension 53, carrying an armature piece 54, said extension 53 being connected with a pull 20 spring 55 having its other end as shown in Figure 5 connected to the adjacent pin 46 heretofore described. Consequently the spring 55 normally pulls the lever 52 down at its left hand end as viewed in Figure 5 with the left hand pawl 25 tooth locked with the bar 44 to hold it against shifting movement.

Above this armature element 54 is disposed the core of a vertical electromagnet 56 carried by a bracket 57 supported by the wall 41. A lateral 30 bracket 58 may be carried from the base plate 10 if desired, for mounting a guide or roller 59 to support the carrier plate 38 at its outer end. The plate 38 also carries a bracket structure 60 for supporting a horizontal solenoid 61, which 35 as best shown in Figure 1 includes a spring pushed core 62 the free end of which is notched to carry an upright pin 63 mounted on one arm of a bell crank lever 64 pivoted on a pin 65 carried by the carrier plate 38. The opposite end 40 of the bell crank lever 64 has a bifurcated end 66 straddling the pin 43 heretofore described.

Resting for free, sliding movement, flatwise on the main slide is a first auxiliary slide 67 having a check receiving opening 68, said slide being 45 passed through the block 13 and provided at its end adjacent the bent end 18 of the bar 17 with oppositely extending ears 69, one of which is pulled by a spring 70 extending alongside the main slide 20 and anchored to an upright pin 71 carried on the base plate 10. The spring 70 obviously acts to pull the slide 67 to abut the ears 69 thereof against the stop 18 which is positioned to register the opening 68 in said auxiliary slide under and in registration with the 55 magazine 15.

Above the first auxiliary slide 67 is similarly positioned a second auxiliary slide 71 having a check opening 72 and also provided with ears like those on the slide 67 for the same purpose 60 and also being pulled by another spring 70 as has been described.

Above the second auxiliary slide 71 is a third slide 73 having a check opening 74 and also provided with ears like those on the slide 67 65 for the same purpose and also being independently pulled by another spring 70 as has been described and for the same reasons.

On top of the upper auxiliary slide 73 is slidably mounted a flat U-shaped plate 75 also movable with the pack of slides through the passageway in the block 13 said plate 75 carrying an upstanding pin 76 to which is connected one end of a pull spring 77 having its other end anchored to a pin 78 fixed in the stationary block 75

13. A stop pin 79 anchored in the plate 75 limits the distance to which the spring 77 can pull the plate 75 into the block 13. This completes the detail description of the structure of the improved check, coin or token handling mechanism.

In the starting position of the parts as shown in Figures 1, 3, 4 and 5, all electric parts such as the motor 26, the electromagnet 56 and the solenoid 61 are deenergized. The spring 36 is operative through the lever 34 to hold the main slide 20 in the position shown in Figure 3 with the opening 21 thereof in registration with the magazine 15. Similarly, the springs 70 hold the three auxiliary slides 67, 71 and 73 in a corresponding position so that their respective openings 67, 72 and 74 also register with each other and with the magazine 15, as well as with the main slide opening 21. Further, the spring 77 holds the U-plate 75 in the position also shown in Figure 3 so that its U straddles the bore formed by the registering check drop openings. As a result, when the magazine 15 is loaded with checks, or the like, they gravitate downwardly through these registering openings so that the column of checks rests on the tight bottom provided by the top surface of the base plate 18 adjacent the dispenser chute 11.

Each of the slides or ejectors 20, 67, 71 and 73 in the present illustrative embodiment is of a thickness equal to the thickness of two checks when superimposed flatwise. Consequently, by gravitation, there would be eight checks held by the four slide openings at the lower end of the column of checks.

By means of the improvements of this invention the two checks lodged in the main slide 20 may be handled and ejected from the magazine through the chute 11 without operating any of the auxiliary slides, or slide 67 may be operated conjointly with the main slide 20 to handle and dispense four checks simultaneously; or slides 67 and 71 may be operated conjointly with the main slide 20 for simultaneously dispensing six checks; or within the limits of the present embodiment of the invention all three auxiliary slides 67, 71 and 73 may be moved conjointly with the main slide 20 to dispense eight checks simultaneously.

50 When the motor 26 is energized by a suitable switch and circuit not shown and with the control bar 44 having its stepped end drawn and held by the lever 64 away from the ends of the auxiliary slides 67, 71 and 73, the main slide 20 operates to and fro alone through the gear drive connections described which through the pinwheel 32 drives the wall 24 and slide 20. As long as the motor operates the main slide 20 will reciprocate and dispense two checks on each stroke or forward pass. When the motor is deenergized the lever 34 pushes the slide 20 back to its starting position. All the while that the slide 20 operates alone the carrier plate 38 and parts mounted thereon also reciprocate but the stepped end of the cross rack bar 44 merely passes by the proximate ends of the auxiliary slides which are retained in inoperative normal positions by the pull of their respective springs:

70.

Normally, and when the slide 20 operates alone, the stepped end of the rack bar 44 is so positioned and held by the lock pawl 52 that the lower step 48 is positioned one rack bar step away from the adjacent end of the first auxiliary

slide 67. Obviously, now, if it is desired to move the slide 67 conjointly with the main slide 20 it will be necessary to release the rack bar 44 and shift it one step so that the step 48 will lie in a position to abut and pick up the end of the slide 67 when the carriage 38 moves with the slide 20. Accordingly, by energizing the electromagnet 56 the armature 54 is attracted to raise the left hand tooth of the pawl lever 52 as viewed in Figure 5 and then the solenoid core 62 which is deenergized is pushed by its spring shown in Figure 1, to swing the bell crank lever 64 to move the pin 43 and shift the freed rack bar 44 in a direction to cause the step 48 to be moved across the end of the slide 67. The magnet 56 will, of course, be but momentarily energized so that the spring 55 is immediately operative to swing the pawl lever 52 back to its rack bar locking position. This lever 52 is so proportioned that the right hand dog thereon, as viewed in Figure 5 controls the range of shift of the bar 44 whereby the said bar 44 can move only far enough to place the step 48 in line with the slide 67 and so that the other steps 49 and 50 are not effective to engage the other slides 71 and 73 with which they respectively cooperate until desired.

Now with the rack bar step 48 set as described when the motor 26 is again energized the main slide 20 makes its stroke moving the carrier 38 therewith and causing the step 48 to abut and move the auxiliary slide 67 conjointly with the main slide 20 so that four checks will be dispensed from the magazine with every pass of the two slides as long as the motor operates. In the meanwhile the springs 70 for the two auxiliary slides 71 and 73 hold the latter against operation in an obvious manner.

In a similar manner the rack bar may be released by the electromagnet 56 to enable the solenoid spring to operate the bell crank lever 64 to shift the next step 49 into a position where it will pick up and move the slide 71 conjointly with the slides 20 and 67 to dispense six checks. In the same way the step 50 can be caused to move the top slide 73 with the three slides 20, 67 and 71 to dispense eight checks on every stroke.

Sometimes because of worn checks and resultant thickness variations when a column of checks eight checks high is moved, a ninth check on top of the column would serve to jam the slides. When this tendency occurs the top, or ninth check abuts against the compensator slide 75 and moves therewith and with the eight checks in the other four slides and is dispensed therewith to prevent damage, or jamming.

In resetting the device so that only the main slide 20 can function alone, the solenoid 61 is energized by an appropriate switch and circuit not shown, whereupon the core 62 is drawn to swing the bell crank lever 64 reversely and move the rack bar 44 in the opposite direction so as to set back the steps where they will be positioned so that they cannot engage the auxiliary slides.

Any desired number of auxiliary ejectors, or slides, greater or less than the number herein shown, may be used without departing from the invention.

The device has great utility in many places where checks or coins are to be handled. For instance, the unit would make an ideal change maker in dispensing five cent pieces, for example. Any suitable form of key board or sets of manually or otherwise controlled contacts may be used to control the operation of the slides,

and such electrical mechanism has not been shown since it is deemed unnecessary to the purposes of this disclosure.

In game apparatus for amusement purposes 5 the unit could be associated with such an organization as shown for example in Seiden et al. Patent 2,010,966 issued August 13, 1935. In such organization the coin chute used to release the game for play would control circuits to 10 operate setting of the rack bar in relation to the auxiliary slides.

It is the intention to cover herein all changes and modifications of the example shown for 15 purposes of the disclosure which do not in material respects constitute departures from the spirit and scope of the invention.

What is claimed is:

1. In a check handling apparatus including an 20 upright magazine and a main slide movable to and fro across one end thereof to receive and eject checks therefrom, a motor device having means to drive the main slide, the combination therewith of a pack of superimposed movable auxiliary slides operatively associated with the 25 main slide and the magazine to receive and move additional checks from the magazine, and means carried on the main slide for moving one or more of the auxiliary slides when the main slide is moved, said last mentioned means being movable crosswise of the path movement of the slides to engage the ends thereof and also being bodily movable with the main slide.

2. In a check handling apparatus including an 30 upright magazine and a main slide movable to and fro across one end thereof to receive and eject checks therefrom, a motor device including means to drive the main slide, the combination therewith of a pack of superimposed auxiliary slides movable with the main slide in relation to 35 the magazine to receive and move additional checks from the magazine, each slide being movable against the resisting force of resilient means, and means carried by and movable with the main slide to move one or more of the auxiliary slides, 40 said last mentioned means being also movable at right angles to the movement of the auxiliary slides for determining which of the latter are to be moved with the main slide.

3. In a check handling apparatus a base 45 plate, a block carried thereon having a passage formed therethrough, a pack of slides mounted on the base plate for movement through the passage in the block, said block carrying an upright check magazine with a stack of checks 50 therein which gravitate into the block to be received and moved by the slides, one of the slides being a main slide and the others auxiliary slides, means for moving the main slide, and means movable bodily with the main slide and carried 55 thereby to move one or more or all of the auxiliary slides therewith to dispense checks from the magazine, said latter means comprising a translationally movable member movable in a path substantially at right angles to the path of movement of the slides.

4. In a check handling apparatus a base plate, a block carried thereon having a passage formed therethrough, a pack of slides mounted on the base plate for movement through the passage in 70 the block, said block carrying an upright check magazine with a stack of checks therein which gravitate into the block to be received and moved by the slides, one of the slides being a main slide and the others auxiliary slides, stops on the auxiliary slides, springs pulling the auxiliary slides

in a direction to abut the stops against the block, means for moving the main slide to receive and dispense a check from the magazine, and means carried on the main slide for simultaneously moving one or more or all of the auxiliary slides with the main slide against the pull of the springs to receive and dispense additional checks from the magazine, said last mentioned means being movable bodily with the main slide and also having movement along a line crosswise of the path 10 of movement of the slides. 5

5. In a check handling apparatus a base plate, a block carried thereon having a passage formed therethrough, a pack of slides mounted on the base plate for movement through the passage in 15 the block, said block carrying an upright check magazine with a stack of checks therein which gravitate into the block to be received and moved by the slides, one of the slides being a main slide and the others auxiliary slides, means for moving the main slide, a carrier bodily movable with the main slide, and means on the carrier and movable therewith to pick up and move one or more or all of the auxiliary slides when the main slide moves, said means on the carrier being 20 mounted for translational movement along a line disposed substantially at a right angle to the path of movement of the slides. 25

6. In a check handling apparatus including an upright magazine and a main slide movable 30 to and fro across one end thereof to receive and eject checks therefrom, a motor device including means to drive the main slide, the combination therewith of a pack of movable auxiliary slides carried above the main slide to receive and move 35 additional checks from the magazine, a carrier on and movable bodily with the main slide, a ratchet device movably mounted on the carrier for movement along a line at right angles to the path of movement of the slides and including 40 means for positioning it to pick up one or more or all of the auxiliary slides for simultaneous movement with the main slide to receive and dispense checks from the magazine.

7. In a check handling apparatus including 45 an upright magazine and a main slide movable to and fro across one end thereof to receive and eject checks therefrom, a motor device including means to drive the main slide, the combination therewith of a pack of movable auxiliary 50 slides carried above the main slide to receive and move additional checks from the magazine, a carrier on and movable with the main slide, a normally locked movably mounted ratchet device carried on the carrier for movement along 55 a line at right angles to the path of movement of the slides, and electromagnetic releaser means for positioning the ratchet device in one direction to pick up one or more or all of the auxiliary slides for movement with the main slide whereby 60 said slides conjointly receive and dispense checks from the magazine.

8. In combination, an upright check magazine having a main slide movable to and fro across the lower end of the magazine to receive and remove checks therefrom, an auxiliary slide mounted above and parallel with the main slide for movement with the main slide to receive and eject additional checks from the magazine, carrier means included in the main slide to one side 70 thereof and movable therewith, an optionally movable member carried on the carrier means and movable at substantially right angles to the direction of movement of the slides, said optionally movable member adapted to be positioned to 75

abut and move the auxiliary slide conjointly with the main slide when the latter moves, and means to move the main slide.

9. In combination, an upright check magazine having a main slide movable to and fro across the lower end of the magazine to receive and remove checks therefrom, a number of auxiliary slides mounted above and parallel with the main slide for movement with respect to each other and for movement with the main slide to receive and eject additional checks from the magazine, the main slide including a lateral extension movable therewith and carrying an optionally movable member for movement in a path substantially at right angles to the path of movement of the slides, said optionally movable member being provided with a stepped end adapted to abut in one direction of movement one or more or all of the auxiliary slides to move same conjointly with the main slide, and means to move the main slide.

10. In a check handling apparatus, an upright check magazine, a main slide cooperable with the lower end thereof to eject a check therefrom, a motor having means to drive the main slide, the combination therewith of an auxiliary slide mounted above the main slide for movement to eject an additional check from the magazine, a manually controlled electromagnetically moved ratchet member in one direction of movement adapted to be set to cause the two slides to move conjointly, and means for oppositely moving the member to enable the main slide to operate alone.

11. In a check handling apparatus, an upright check magazine, a main slide cooperable with the lower end thereof to eject a check therefrom, a motor including means to drive the main slide, the combination therewith of an auxiliary slide mounted above the main slide for movement to eject an additional check from the magazine, a manually controlled electromagnetically moved ratchet member movable with the main slide and adapted in one direction of movement to be set to cause the two slides to move conjointly, and means including an electromagnetic means for moving the member in an opposite direction to enable the main slide to operate alone.

12. In a check handling apparatus having a base carrying a motor device and an upright magazine containing the checks to be dispensed, the combination therewith of a plurality of superimposed ejector slides carried for movement in relation to the magazine to eject checks therefrom, a spring pulled lever pivotally carried on the base with the lever constantly engaging the lower slide, means included in the lower slide adapted to be moved by the motor device to cause the lower slide to be moved to ejector position in relation to the magazine against the pressure of the spring pulled lever, and means for causing any of the other slides in order from the bottom upwardly to move to ejection position with the lower slide, said means being carried entirely on the lower slide for movement therewith and for additional translational movement crosswise in relation to the path of travel of the lower slide and formed for engaging respectively the ends of the upper slides.

13. In a check dispenser having a magazine and a main slide movable in relation thereto to eject checks therefrom, an auxiliary slide carried loosely on the main slide for dispensing additional checks from the magazine, the combination with said main slide of a side extension plate rigidly connected thereto to move therewith, a bar car-

ried on the plate for bodily movement therewith and also for relative movement along a line crosswise of the path of movement of the auxiliary slide, means movable with the plate for moving the bar relative to the plate to engage an end of the auxiliary slide in abutting relationship whereby when the main slide moves the auxiliary slide and parts on the extension plate move bodily therewith.

14. In a check dispenser having a magazine and a main slide movable in relation thereto to eject checks therefrom, an auxiliary slide carried loosely on the main slide for dispensing additional checks from the magazine, the combination with said main slide of a side extension plate rigidly connected thereto to move therewith, a rack bar carried on the plate for bodily movement therewith and also for relative movement along a line crosswise of the path of movement of the auxiliary slide, means yieldingly urging said rack bar from an inoperative position to a position in end abutting relationship to the auxiliary slide, an escapement for locking said bar against such crosswise movement, and electromagnetic means for releasing the escapement to cause the bar to move to the position abutting the auxiliary slide whereby when the main slide moves the auxiliary slide will move therewith.

15. In a check dispenser having a magazine and a main slide movable in relation thereto to eject a check therefrom, a superimposed pack of auxiliary slides carried on the main slide and adapted for movement therewith to dispense additional checks, the combination with said main slide of an extension plate carried thereby for movement therewith, a rack bar carried on the plate for bodily movement therewith and also for relative movement crosswise of the path of movement of the auxiliary slides, the bar having a stepped end adjacent the slides, means for urging said bar to a position where the stepped end thereof will be moved successively to abut the ends of the auxiliary slides, an escapement cooperable with the rack bar to hold it against such crosswise movement, means to release the escapement in a manner to cause the stepped end of the bar to engage an auxiliary slide for each step of movement of the bar in one direction whereby when the main slide operates such auxiliary slides as are abutted by the stepped end of the bar will move therewith, and means for moving the bar in an opposite direction to enable the bar to be reset in an inoperative position to enable the main slide to operate alone.

16. In a check handling apparatus having an upright magazine containing checks to be dispensed and a main slide movable to and fro across its lower end to receive and remove a check from the magazine, an auxiliary slide carried adjacent the main slide for similar to and fro movement with respect to the magazine to receive and remove an additional check from the magazine, and means to move the main slide, the combination with said auxiliary slide of means to move the auxiliary slide optionally with the main slide, said means comprising a member carried on and for movement with the main slide, said means further having independent translational movement crosswise of the path of movement of the main slide, and means to move the said means crosswise as stated to a position abutting an end of the auxiliary slide.

CHARLES J. BREITENSTEIN.
DONALD E. HOOKER.
